UNITED STATES PATENT OFFICE.

JOHN B. FORD, OF FERN CREEK, KENTUCKY.

LARD-PRESS.

SPECIFICATION forming part of Letters Patent No. 262,284, dated August 8, 1882.

Application filed June 28, 1882. (Model.)

To all whom it may concern:

Be it known that I, JOHN B. FORD, a citizen of the United States, residing at Fern Creek, in the county of Jefferson and State of Kentucky, have invented certain new and useful Improvements in Lard-Presses; and I do hereby declare that the following is a full, clear, and exact description of the same, reference being had to the annexed drawings, 5 making a part of this specification, and to the letters and figures of reference marked thereon.

Figure 1 of the drawings is a top plan view of my invention; Fig. 2, a longitudinal section thereof, and Fig. 3 a detail view of one of the 15 receiving-vessels.

The object of the present invention is to provide a simple, strong, and durable machine for pressing lard, fruit, &c., that will perfectly do its work with comparatively little trouble, and 20 with great leverage power. These several objects I attain by the construction, substantially as shown in the drawings and hereinafter described and claimed.

In the accompanying drawings, A represents a suitable bench or table of rectangular shape, formed with circular grooves *a*, around the outer sides of which are secured flanged plates or circular metal bands *b*, extending above the top of the bench or table. Within 25 the grooves *a* are seated cylindrical receiving-vessels *B*, provided with feet *c* to raise the vessels above the bottom of the grooves to admit the escape of the pressed material into the trough *d*, where it is discharged into a receptacle placed under the spout *e* to receive it. The vessels *B* are provided with suitable handles, *f*, for raising them up out of the grooves and removing them from the bench or table A.

It should be noticed that the vessels *B* have 30 no bottoms, but are simply in the form of an open hollow cylinder, which surround the slatted tubs *C*, which also rest in the grooves *a*.

Within the tubs *C* are located followers *D*, having upon their upper ends pins *g* for centering thereon the plungers *E*, which loosely rest 35 on the followers.

The screw-threaded end of a rod, *F*, extends down and through a screw-threaded bushing, *h*, secured around an opening made through the bench or table A.

The upper end of the rod *F* is formed with a square or other equivalent head, *i*, for connecting thereto a crank of any suitable construction, by means of which the rod *F* is operated.

To the rod *F*, directly below the head *i*, is 55 loosely fitted the presser-bar *G*, of sufficient length to extend at each end over the plungers *E*. By turning the screw-threaded rod *F* in the proper direction the ends of the presser-bar *G* will be brought with great power of 60 pressure upon the plungers *E*, which will force the followers *D* down upon the lard or other material being pressed, forcing it out through the spaces in the slatted buckets *C*, and out under the edge of the vessels *B* into trough *d*. The 65 circular metal bands *b* prevent the lard from running over the bench or table A, and also serve as retaining-flanges for the vessels *B*.

The vessels *B*, tubs *C*, followers *D*, and plungers *E* are all detachable from each other, and 70 removable from the bench or table A by simply turning at right angles to the length of the bench or table the presser-bar *G*, thus allowing the several parts to be removed.

Having now fully described my invention, 75 what I claim as new, and desire to secure by Letters Patent, is—

The removable vessels *B* having feet *c*, the slatted tubs *C*, followers *D*, and plungers *E*, in combination with the bench or table A, 80 formed with grooves *a*, and the screw-rod *F*, having loosely connected to it the presser-bar *G*, constructed and arranged to operate substantially as and for the purpose set forth.

In testimony that I claim the above I have 85 hereunto subscribed my name in the presence of two witnesses.

JOHN BRECKENRIDGE FORD.
